[57] CLAIM

The ornamental design for a surgical drain tube, as
shown and described.

DESCRIPTION

FIG. 1 is a perspective view of a surgical drain tube
showing my new design, the side opposite being identi-
cal;

FIG. 2 is an end view thereof;

FIG. 3 is a perspective view of an alternate embodiment
of FIG. 1;

FIG. 4 is an end view thereof;

FIG. 5 is a perspective view of another alternate em-
bodiment of FIG. 1; and

FIG. 6 is an end view thereof.
